UNITED STATES PATENT OFFICE.

ROBERT S. MOSS, OF CHICAGO, ILLINOIS, ASSIGNOR OF ONE-FOURTH TO ARTHUR ROBERTS, OF EVANSTON, ILLINOIS, AND ONE-FOURTH TO EDWARD ANDERSON, OF CHICAGO, ILLINOIS.

COKE-OVEN.

1,025,419.

Specification of Letters Patent.

Patented May 7, 1912.

Application filed February 7, 1911. Serial No. 607,148.

To all whom it may concern:

Be it known that I, ROBERT S. Moss, a citizen of the United States, residing at Chicago, in the county of Cook and State 5 of Illinois, have invented certain new and useful Improvements in Coke-Ovens, of which the following is a specification.

My invention relates to that type of coking apparatus in which the air which supplies the oxygen for the combustion of the 10 burning gases, used to heat the retort or oven, is continuously heated by the interchange of the heat of the products of combustion through the intervening walls of 15 their respective passages.

The principal object of the present invention is to provide in a coke oven a simple arrangement of flues for the combustible gases, for the waste products, and for the 20 admission of air, all of which shall be so arranged with respect to each other that a most general distribution of heat around the coking chamber will be effected, and that the air prior to its admission with the 25 combustible gases will be preheated without consuming an appreciable amount of live heat from the flues surrounding the oven.

The invention further consists in the features of construction and combination of 30 parts hereinafter described and claimed.

In the drawings, Figure 1 is a transverse section of an oven on line 1—1 of Fig. 4; Fig. 2 a side elevation of an oven with the walls partly broken away; Fig. 3 a transverse section of an oven on line 3—3 of Fig. 35 4; Fig. 4 a horizontal section on line 4—4 of Fig. 1; Fig. 5 a transverse section of an oven showing a modified form of construction; Fig. 6, a horizontal section through 40 several ovens showing an arrangement by which a single air flue is utilized between two adjacent ovens; Fig. 7, a view similar to Fig. 6, showing vertical supports extending throughout said air flue; and Fig. 8 a 45 detail of the lower end of an oven.

In the coke oven of the retort or closed chamber type, the heat necessary to carry on the coking operation is generally supplied by the combustible gases that are expelled 50 from the coal.

In the present invention it is sought to provide means by which air may be preheated without impairing the efficiency of the oven, which air may then be mixed with

the combustible gases to support the combustion and increase the intensity of the heat thereof.

In describing my invention, reference will be made to one oven only, but it is to be understood, that in actual operation any desirable number of such ovens may be arranged to form a battery, and all the ovens being identical, a minute description of only one oven is deemed necessary.

My invention comprises a closed oven 6 of usual fire brick construction, having an arched roof 7. In the form of oven illustrated in the drawings, there is shown at the front end thereof, a heavy fire brick construction 21, formed with an insulating 65 air space 22, and provided on the outside thereof with a vertically sliding door 23 of usual construction. During the coking operation, it is intended that said door shall be sealed with clay, or other suitable plastic 70 substance, to effectually prevent the radiation of heat from within the coking chamber to the outside air. It is customary to provide ovens of this type with openings in their roof portions through which the distilled 75 gases are drawn off into an exhaust flue, and thence educted away to be relieved of their by-products. These combustible gases are then returned to the ovens through pipes 8 to be utilized to maintain the heat 80 around the ovens.

As best shown in Fig. 3, the walls surrounding the ovens are traversed on one side thereof by a series of vertical flues 9, which are connected by passages 10, crossing under the oven to a series of flues 11, which extend vertically along the opposite side thereof. Close to the top of the oven, a transverse passage 12 connects the flue 11 with another vertical flue 13 which leads 90 downward to a flue 14 which is in connection with the stack. The flue which is represented by the passages 9, 10, and 11, is designed for the reception of the combustible gases and products of combustion. Its position with regard to the closed oven 6 is such that the heat produced by complete combustion of the combustible gases therein will be imparted to effect the distilling of the 95 coking coal within the oven. These flues, for the reception of combustible gases, are arranged, as best shown in Figs. 2 and 4, in series with one another, being positioned 100 105

throughout the length of the oven at proper distances to communicate the necessary heat to the coking chamber.

The supply pipes 8, which are arranged 5 in parallel order along each oven, have branch connections 15, provided with controlling valves 16, located directly in alignment with the flues 9, so that nozzles 17 may extend therein. In the arrangement of the 10 series of heating flues surrounding the coking chamber, the passages 9 in which the nozzles enter, are situated on opposite sides of the oven throughout the series, so that the gas entering through the nozzles is admitted, as regards the series of flues, first 15 on one side of the oven and then the other. The passages 9, 10, 11, 12, and 13, being arranged in alternate order, as indicated in 20 Figs. 1, 2, 3, and 4, it follows that the nozzles are positioned in alternate relation, in order to connect with the flues 9. This 25 alternating arrangement of the flues insures throughout the length of the oven, even distribution of heat from the combustible gases, which is highly essential to the production of an even quality of coke.

In order that the combustion of the gases in the flues surrounding the coking chambers may be most complete, it is desirable 30 that air which has been raised to a very high temperature, be admitted to support said combustion. In my invention this heating of the air to prepare it for mixture with the combustible gases is accomplished 35 by providing flues 18 adjacent the passages 9 and 13, extending longitudinally along the oven, having openings 19 in their lower portions, and connections 20 with the passages 9 at the points where the nozzles project the combustible gases into the flues. The flues 18 lie adjacent the flues 13 in 40 which combustion of the gases is taking place, and the radiant heat is imparted by the gases to the walls separating the said flues, by which means the heat is communicated to the air in the passage 18. The air during its passage from the opening 19 to the top of the oven is raised to a very 45 high temperature and is rendered suitable to support combustion of the gases surrounding the coking chamber. The necessary quantity of oxygen to be supplied and the amount of air that can be properly heated where this design of oven is employed, can of course, be properly predetermined before its construction to secure the maximum degree of efficiency. The location of the air flues 18 with respect to the heating flues is such that only waste heat is 50 utilized to raise the air to its high temperature. There is considerable heat imparted by the combustible gases that is not absorbed by the coking chamber, but is communicated throughout the brick work and 55 eventually radiates off into the air. It is

designed that the air flues shall be arranged to utilize such heat. It is readily apparent that when a series of ovens are banked together to form a battery, that the air passages will lie intermediate the coking chambers and that the heat imparted to them will be communicated from the ovens on either side. It is also apparent that when said 70 passages are thus positioned intermediate heating flues, the air in said passages will be 75 raised to a greater temperature than where heat is radiated to it from one side only, as is illustrated in the drawing.

In Fig. 5 is shown a modified form of the oven just described. It differs from my 80 preferred form mainly in that the horizontal flue 10 under the oven is eliminated, and the passages 10, 12, and 13, for combustible gases are all situated, as regards any one of the series of the flues, on one side of the 85 oven. The flues 18 in which the air is heated to a high temperature are in the form of pipes or tubes lying in the passages 13, and are made with openings at the lower 90 end for the admission of the air, and connections at the upper end to deliver the heated air at the point where the combustible gases enter the flues.

The introduction of the heated air and combustible gases to the heating flues in the 95 oven of my invention is at points substantially level with the top of the oven and along the length thereof. The flues extend downwardly along the coke chamber, then below the oven, and upwardly again, surrounding the said coking chamber on three sides. The flues do not extend over the oven in any place, the sides and lower portion of the coking chamber being subjected as is most desirable to the heat produced by 100 combustion of the gases in the flues. Moreover, it is to be noted that the maximum heat produced by the combustion of the gases in the heating flues will be delivered relatively close to the top of the oven near the point 105 of induction of said gases which will cause the coking operation to begin at the top layer of coal and proceed downward.

Inasmuch as the complete combustion of the gases produces the maximum temperature in the flue 9, it is evident that the coal adjacent that side of the oven tends to coke sooner than that on the other side thereof. In order to overcome such an objection, I have provided a unique construction of each 115 series of flues, arranging them alternately so that throughout the length of the oven, the flues 9, in which the gases are introduced, extend along the coking chamber on each side, thereby effecting an equal distribution 120 of the heat around the oven. A further advantage is secured in introducing the gases to the flues through nozzles at the top of the oven. Whenever it is desired to regulate the 125 flow of said gases through the nozzles, the 130

controlling valves on said nozzles are readily accessible for adjustment. It may also be necessary from time to time to clean the nozzles, and this is greatly facilitated by having them positioned where they may be readily removed.

5 In the embodiment of my invention, I have illustrated in the drawings a form of construction which is designed to assist in an 10 understanding thereof, but I do not desire to be limited in any way to the particular form of construction shown, since it is readily apparent that it might be desirable to construct an oven differing somewhat in 15 form that will embody the principles of my invention.

I claim:

1. In a coke oven, a retort, a series of heating flues extending around said retort, means 20 for admitting gas to said flues, the induction ends of said flues being arranged on opposite sides of the retort and alternately with respect to each of said series of flues, means for educting the products of combustion, air 25 flues communicating at one terminus thereof with said heating flues, said air flues extending between their termini in close proximity to the heating flues, whereby the radiant heat from the burning gas is utilized 30 to heat the air prior to its commingling with the gas, substantially as described.

2. In a coke oven, a retort, a series of heating flues extending around said retort, means for admitting gas to said flues at a point 35 substantially level with the top of said retort, the induction ends of said flues being arranged on opposite sides of the retort and alternately with respect to each of said series of flues, means for educting the products of 40 combustion, air flues communicating at one terminus thereof with said heating flues, said air flues extending between their termini in close proximity to the heating flues, whereby the radiant heat from the burning gas is utilized 45 to heat the air prior to its commingling with the gas, substantially as described.

3. In a coke oven, a plurality of retorts, a series of heating flues extending around each

of said retorts, means for admitting gas to said flues, the induction ends of said flues being arranged on opposite sides of the retorts and alternately with respect to each of said series of flues, means for educting the products of combustion, air flues communicating at one terminus thereof with said heating flues, said air flues extending between their termini in close proximity to the heating flues and intermediate the same, whereby the radiant heat from the burning gas is utilized to heat the air prior to its commingling 60 with the gas, substantially as described.

4. In a coke oven, a plurality of retorts, a series of heating flues extending around each of said retorts, means for admitting gas to said flues at a point substantially level with 65 the top of said retort, the induction ends of said flues being arranged on opposite sides of the retort and alternately with respect to each of said series of flues, means for educting the products of combustion, air flues 70 communicating at one terminus thereof with said heating flues, said air flues extending between their termini in close proximity to the heating flues and intermediate the same, whereby the radiant heat from the burning 75 gas is utilized to heat the air prior to its commingling with the gas, substantially as described.

5. In a coke oven, a retort, a series of flues extending in a direction longitudinally of 80 said retort, and terminating in planes marking approximately the upper and lower edges of said retort, a portion of said flues being heating flues, a portion return flues, and a portion air flues, the heating flues lying 85 closest to the retort, the air flues lying farthest from the retort, and the return flues being intermediate the heating and air flues, whereby a relatively thick wall is interposed 90 between the heating and air flues, and a relatively thin wall interposed between the return and air flues, substantially as described.
